[57] CLAIM

The ornamental design for a hand-grip for a luggage case, as shown and described.

DESCRIPTION

FIG. 1 is a top plan view of a hand-grip for luggage case showing my new design;

FIG. 2 is a bottom plan view thereof;

FIG. 3 is a front elevational view thereof;

FIG. 4 is a rear elevational view thereof;

FIG. 5 is an end elevational view thereof; and FIG. 6 is an end elevational view thereof, opposite to and identical to FIG. 5.

The anchoring tabs are shown in broken lines for illustrative purposes only.

FIG. 1

FIG. 2

FIG. 3

FIG. 4

FIG. 5

FIG. 6
